UNITED STATES PATENT OFFICE.

NAOSABURO MINORIKAWA, OF TOKYO, JAPAN.

STOKING APPARATUS.

1,346,379.

Specification of Letters Patent. Patented July 13, 1920.

Application filed May 7, 1917. Serial No. 163,936.

To all whom it may concern:

Be it known that I, NAOSABURO MINORIKAWA, a subject of the Emperor of Japan, residing at No. 4 Hatsunecho, Koishikawa-
5 Ku, city of Tokyo, Japan, engineer, have invented certain new and useful Improvements in Stoking Apparatus, of which the following is a specification.

This invention relates to improvements in 10 grates for furnaces for steam boilers and the like, one object of the invention being to effect improvements in the construction of the grate bars; another object being to effect improvement in the construction of the 15 section arranged in the spaces between the grate bars, and another object being to provide improved means for shaking out the ashes and removing the clinkers without disturbing the lumps of unburned coal on the 20 grate bars.

With the above and other objects in view the invention consists in the construction, combination and arrangement of devices hereinafter described and claimed.

25 In the accompanying drawing:

Figure 1 is a longitudinal sectional view of the flame tube of a boiler provided with my improved grate.

Fig. 2 is a longitudinal horizontal sec- 30 tional view of the same showing some of the sections in place and also showing some of the grate bars in plan without the sections.

Fig. 3 is a vertical transverse sectional 35 view of the same.

Fig. 4 is a sectional plan of a modification of my invention.

Fig. 5 is a detail vertical sectional view of the same.

40 Fig. 6 is an elevation of one of the sections, constructed in accordance with a modification of my invention.

Fig. 7 is a detail longitudinal sectional 45 view of a portion of one of the bars showing the form of the rod 17.

Fig. 8 is a transverse sectional view of portions of two of the bars and showing the racking attachment and its means of support.

50 In accordance with my invention, each grate bar 1 has a centrally arranged slot 3 which extends from end to end and also from top to bottom of the bar. On the outer side of the bars, at their lower edges, are flanges 3^a. Sections 4 are arranged between the grate bars, at right angles thereto, and

thereupon and are supported by the flanges 3^a, the said sections being readily removable from between the grate bars and being adapted to be readily lifted therefrom. Each 60 section has a centrally arranged opening 4^b for the passage of air and is also provided on opposite sides, at the edges, with flanges 4^c, the said flanges serving to space the sections somewhat apart to form air passages 65 between them, as shown in Fig. 2. The upper ends of the sections may be semi-circular in form as shown in Fig. 3, or they may be of triangular form as shown in Fig. 6. Each section 4 has a lower extension 15 70 which projects below the grate bars and is provided with openings 16, 18.

The openings 18 of the various sections are in alinement with one another and are arranged for the reception of a straight rod 75 by means of which the sections can be arranged in the required normal position. A bent working bar or rod 17 can be inserted from the front end of the furnace through the opening 16 to move the sections up and 80 down in a wave-like movement, according to the shape of said working rod, and to thereby thoroughly dislodge ashes from between said sections.

Each grate bar has guide flanges 2 on the 85 inner side of its walls, at opposite sides of its slot 3. Each guide flange has an elevated central portion 2^a at the upper side of the bar, has oppositely inclined depending portions 2^b near its end and has lower, horizontal end portions 2^c. Above the said end portions 2^b, and spaced therefrom, are covering flanges 6, guide-ways 7 being formed between the inner ends of said covering flanges and the inclined portion of said flanges 2, as 90 shown clearly in Fig. 1. The side walls of the grate bars are provided at points near the front ends of the grate bars with downwardly extending portions 13. Rollers 14 are revolvably mounted between the portions 100 13 as shown. A raker 12 may be arranged and operated on any one of the rollers 14 and has an upturned portion at its inner end to extend up into a slot 3 and which is provided with an enlarged head 11 to bear and 105 slide on the guide flanges 2. When the raker is moved lengthwise back and forth said guide flanges serve to guide the head 11 and cause the same to thoroughly dislodge the ashes and clinkers, the ashes falling downwardly through the slot 3 and the clinkers falling through the guide-ways 7 and drop-

ping from the ends of the grate bars at points under the covering flanges 6, as will be understood.

In the form of the invention shown in Figs. 4 and 5 some of the sections 4 are omitted at the inner ends of the grate bars, to provide openings between the grate bars through which ashes can readily drop, a transverse bar 9 is provided which is arranged on the inner end of the grate bars and covering bars 10 are arranged on said transverse bar and above the grate bars and the spaces between them.

Having thus described my invention, I claim:

1. A grate bottom comprising longitudinally arranged bars spaced apart having flanges on their opposing sides, and removable sections arranged at right angles to the grate bars, in the spaces between the grate bars and bearing on and supported by said flanges.

2. A grate bottom comprising longitudinally arranged bars spaced apart and having flanges on their opposing sides, and removable sections arranged at right angles to the grate bars, in spaces between the grate bars and bearing on and supported by said flanges, said sections having flanges on their opposing sides which serve to space said sections apart to form openings between them.

3. A grate bottom comprising longitudinally arranged bars spaced apart and having flanges on their opposing sides, and removable sections arranged at right angles to the grate bars, in spaces between the grate bars

and bearing on and supported by said flanges, said sections having flanges on their opposing sides which serve to space said sections apart to form openings between them, and said sections also having air openings therein.

4. In a grate of the character described, longitudinally arranged grate bars having flanges on their opposing sides, and sections in the spaces between the grate bars and bearing on and supported by said flanges, said sections being removable independently of each other and being also vertically movable between the grate bars and being further provided with openings for the reception of a rod wherewith to impart vertical reciprocating motion to said sections.

5. In a grate of the character described, longitudinally arranged grate bars having flanges on their opposing sides, and sections in the spaces between the grate bars and bearing on and supported by said flanges, said sections being removable independently of each other and being also vertically movable between the grate bars and being further provided with openings for the reception of a rod therewith to impart vertical reciprocating motion to said sections, the said openings of the respective sections being arranged at different elevations.

In testimony whereof I affix my signature in the presence of two witnesses.

NAOSABURO MINORIKAWA.

Witnesses:

H. YASUMUSA,
HARRY FRANKLIN HAWLEY.
